NONSINKABLE BOAT

Harry C. Berry, San Diego, Calif.

Application September 4, 1934, Serial No. 742,588

3 Claims. (Cl. 114—68)

My invention relates to a boat that will not sink regardless of conditions, and the objects of my invention are:

First, to provide a boat or seacraft which is so arranged and constructed that it will not sink under any known conditions;

Second, to provide a boat of this class which is so constructed and arranged that it passes through the water when traveling with a minimum of water friction;

Third, to provide a boat of this class in which all the decks and cargo space are positioned above the water line;

Fourth, to provide a boat of this class in which the propeller mechanism is positioned between two buoyant streamline floats thereby providing a maximum capacity for propelling mechanism;

Fifth, to provide a boat of this class in which there are mounted propellers at both bow and stern of the boat and may be provided with additional propellers intermediate the ends if desired;

Sixth, to provide a boat of this class in which the propellers and propeller shaft are readily accessible for repair or change;

Seventh, to provide a boat of this class in which the shaft and driving mechanism that is submerged is enclosed in a casing;

Eighth, to provide a boat of this class in which the joints are doubly sealed by a rubber cement supported by metallic tanks under pressure, and

Ninth, to provide a boat of this class which is very simple and economical of construction, durable, efficient in its action, easy to operate, buoyable and non-sinkable.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a top or plan view of my boat showing some of the parts and portions broken away to facilitate the illustration; Fig. 2 is a sectional view through 2—2 of Fig. 1 showing some of the parts and portions in elevation to facilitate the illustration; Fig. 3 is a front elevational view of my boat; Fig. 4 is a fragmentary side elevational view intermediate the ends showing a portion of the outer surface broken away; Fig. 5 is a fragmentary sectional view on an enlarged scale through 5—5 of Fig. 1; Fig. 6 is a fragmentary sectional view on an enlarged scale showing the

joint filled with rubber cement of one side of the main float runner section shown in Fig. 5; Fig. 7 is a sectional view through 7—7 of Fig. 2, and Fig. 8 is an enlarged sectional view of the propeller shaft and casing through 8—8 of Fig. 2.

5

Similar characters of reference refer to similar parts and portions throughout the several views of the drawings.

The float runners 1 and 2, metal tanks 3, rubber cement 4, upper deck 5, lower deck 6, rudders 7, shaft 8, shaft supports 9, propellers 10 and 11, propeller guards 12, sprocket and chain casing 13, sprockets 14 and 15, chain 16, and power plant 17, constitute the principal parts and portions of my non-sinkable boat.

10

The float runners 1 and 2 are streamlined at both bow and stern to reduce to a minimum the friction when passing through the water. They are preferably composed of planks about twelve inches wide and of suitable thickness and may be covered with steel plate on the outer surface and their sides are secured together by a plurality of cross partitions 1a and 2a, as shown best in Fig. 4 of the drawings. Mounted in these runners 1 and 2 and filling the space between the partitions are metallic tanks 3 which are adapted to fill the space between the sides of each of these members 1 and 2 and between the partitions 1a and 2a. These tanks 3 are provided on their outer surface with a rubber cement 4 and are sufficiently yieldable that when air pressure on the interior of the tanks 3 is provided the cement 4 is forced out through the cracks between the planks forming the side walls of the members 1 and 2 and filling the joints and also filling the space between the tanks and its enclosing walls, thus providing means for making the joints tight throughout the whole of the submerged portion of the boat. Pressure is provided for the tanks by means of valves 3a which are used for the entrance of compressed air into the interior of the tanks 3. Thus it will be noted that the tanks are supported on all sides by means of planking secured to the cross partitions and these supports form the float runners 1 and 2.

15

The partitions 1a and 2a extend upwardly above the upper sides of said runners 1 and 2 and these runners 1 and 2 are positioned in considerably spaced relation to each other and parallel to each other, as shown best in Figs. 1 and 7 of the drawings, and are supported in this relation by means of cross members 5a secured to these partitions and extending from one runner to the other, as shown best in Fig. 1 of the drawings. These members are provided with a plu-

45

50

55

rality of cross braces 5b, thus rigidly supporting the members 1 and 2 in their parallel spaced relation to each other.

At the upper side of the members 1 and 2 is provided a lower deck 6 which covers the full space including the width of the members 1 and 2 and at the upper side of the members 5a is provided the upper deck 5 which covers the whole upper surface.

10 It will be here noted that any kind of housing may be supported over this upper deck 5 as desired for the different uses or purposes to which the boat may be put.

15 It will be here noted that the lower deck 6 extends upwardly on an angle at 6a at the bow of the boat to conduct the water under the lower deck 6 in a series of high waves or the like.

20 The boat is propelled through the water by means of propellers 10 and 11 mounted between the float runners 1 and 2, preferably two of these propellers, one near the bow and the other near the stern. They are supported by means of a shaft casing 8a, shown best in Fig. 8 of the drawings, which shaft casing is supported by means 25 of the supports 9 which are provided with bearings 9a for supporting the ends of the shaft casing 8a. Mounted inside of the shaft casing 8a is a journal 8b for supporting the shaft, it being noted that there is a plurality of these supports 30 9 and each of them is bifurcated upwardly some distance above the shaft and above the normal water line and the ends extend in through the lower deck 6 and are secured to the partitions 1a and 2a between the decks 5 and 6, as shown best 35 in Fig. 5 of the drawings.

It will be here noted that other propellers may be mounted on the shaft 8 intermediate the propellers 10 and 11 if desired for increasing the propulsion power of the boat.

40 Secured to the casing 8a is a sprocket and chain casing 13 which is shaped as shown best in Figs. 2 and 7 of the drawings and adapted to enclose the lower portion of the sprocket and chain for operating the shaft. Mounted on the shaft 8 in said casing 13 is a sprocket 14. Mounted on this sprocket 14 is a chain 16 which extends up through the decks 5 and 6 and is mounted on a sprocket 15 in connection with the power plant 17.

50 The supports 9 are supported relatively to each other by braces 9b. Mounted in front of the propeller 11 are propeller guards 12 one at each side of the propeller and extending from the upper deck 5 downwardly on an angle and then backwardly and secured to the lower portion of the front support 9, as shown best in Fig. 2 of the drawings. These are for the purpose of providing a guard against floating objects striking the propeller.

60 Mounted on the rear of the boat between the float runners 1 and 2 and on opposite sides of the rear propeller 10 are tandem rudders 7 which

are for the purpose of guiding the boat and are positioned on opposite sides of the propeller in close relation thereto to provide for efficiency in propelling the boat.

It will be here noted that cargo may be placed 5 between the decks 5 and 6 or in some cases some cargo may be placed in the tanks 3. However, it is highly desirable that sufficient bulkhead space be provided to float the craft and cargo regardless of its position and to float it if one 10 or two of the tanks are damaged so that they leak and fill with water or partially fill with water.

15 It will also be noted that additional tanks may be secured between the members 1 and 2 if desired to provide additional buoyancy in case of heavy loading. It will be noted that tanks may be placed in the space between the decks 5 and 6, if desired, in case of heavy loading.

20 Though I have shown and described a particular construction, combination and arrangement 20 of parts and portions, I do not wish to be limited to this particular construction, combination and arrangement but desire to include in the scope of my invention the construction, combination and arrangement substantially as set forth in the 25 appended claims.

Having thus described my invention, what I claim as new and desire to secure by Letters Patent is:

1. In a non-sinkable boat, a pair of streamlined float runners in parallel spaced relation to each other, spaced decks bridging said float runners and holding them in their spaced relation to each other, said decks connected at their sides and ends forming a hollow, closed buoyant hold, 30 said float runners being hollow and each provided with a plurality of transverse partitions, and tanks filling the hollow spaces in said float runners, said tanks covered with rubber cement adapted to fill the joints and leaks in said float 35 runners around said tanks.

2. In a non-sinkable boat, a pair of streamlined float runners in parallel spaced relation to each other, spaced decks bridging said float runners and holding them in their spaced relation 45 to each other, said decks connected at their sides and ends forming a hollow, closed buoyant hold, said float runners being hollow and each provided with a plurality of transverse partitions, tanks filling the hollow spaces in said float 50 runners, said tanks covered with rubber cement adapted to fill the joints and leaks in said float runners around said tanks, and means for providing air under pressure in said tanks.

3. In a non-sinkable boat, a plurality of metal 55 tanks, a rubber cement covering for the exterior of said tanks, means encasing said tanks, and means for admitting air under pressure to the interior of said tanks whereby the joints of said casing are filled by said rubber cement by the 60 pressure in said metallic tanks.

HARRY C. BERRY.
